EXTENSION STEP LADDER

Frank A. Gatright, Fort Lauderdale, Fla.
Application July 22, 1955, Serial No. 37,092

Term of patent 14 years

(Cl. D15—8)

FIG. 1

FIG.3

Fig. 1 is a perspective view of an extension step ladder showing my new design, with the ladder illustrated in an open non-extended position;

Fig. 2 is a perspective view thereof, illustrating the ladder in open, extended position; and

Fig. 3 is a perspective view of the extension step ladder in folded position.

I claim:

The ornamental design for an extension step ladder as shown.
